(57) **CLAIM**

The ornamental design for a cutting tool, as shown and described.

DESCRIPTION

FIG. 1 is a perspective view of a first embodiment of a cutting tool showing my new design;

FIG. 2 is a front elevational view showing the design for the cutting tool of FIG. 1;

FIG. 3 is a rear elevational view showing the design for the cutting tool of FIG. 1;

FIG. 4 is a left side elevational view showing the design for the cutting tool of FIG. 1;

FIG. 5 is a right side elevational view showing the design for the cutting tool of FIG. 1;

FIG. 6 is a top plan view showing the design for the cutting tool of FIG. 1; and

FIG. 7 is a bottom plan view showing the design for the cutting tool of FIG. 1.

FIG. 8 is a perspective view of a second embodiment of a cutting tool showing my new design;

FIG. 9 is a front elevational view showing the design for the cutting tool of FIG. 8;

FIG. 10 is a rear elevational view showing the design for the cutting tool of FIG. 8;

FIG. 11 is a left side elevational view showing the design for the cutting tool of FIG. 8;

FIG. 12 is a right side elevational view showing the design for the cutting tool of FIG. 8;

FIG. 13 is a top plan view showing the design for the cutting tool of FIG. 8; and,

FIG. 14 is a bottom plan view showing the design for the cutting tool of FIG. 8.

The broken lines shown in FIGS. 1-7 illustrate portions of the cutting tool that form no part of the claimed design.

1 Claim, 10 Drawing Sheets
